COMPRESSOR PISTON COOLING SYSTEM
Anthony J. Waibel, Painted Post, N.Y., assignor to Ingersoll-Rand Company, New York, N.Y., a corporation of New Jersey

Filed Nov. 25, 1958, Ser. No. 776,311

1 Claim. (Cl. 277—74)

The invention relates to compressors, and more particularly to a cooling system for the piston of high pressure reciprocating gas compressor.

This application is a continuation-in-part of my pending application Serial No. 579,328, filed April 19, 1956, now abandoned.

One object of this invention is to provide such a cooling system which is readily adaptable to existing compressor designs.

Another object is to provide a cooling system which is relatively inexpensive in construction.

Another object is to provide a cooling system in which the coolant is recovered.

Further objects will become obvious from the following specification and drawings in which,

FIGURE 1 is a longitudinal section showing one form of the invention adapted to a high pressure compressor,

FIG. 2 is a view of the cooling fluid distributing ring for the shaft, and

FIG. 3 is an enlarged longitudinal section showing another form of the invention shown in FIGURE 1.

Referring to the drawings, the invention is shown adapted to a conventional high pressure reciprocating gas compressor. The compressor shown by way of illustration comprises, in general, a casing 10 having a central bore 12 housing a plurality of pressure seals 14 mounted on a reciprocating plunger type piston 16. The free end of the piston reciprocates in a compression chamber 18 formed in a cylinder 20 mounted in one end portion of the bore 12. A cap member 22 is mounted in the opposite end of the bore 12 and bolted to the casing 10. The cap serves to clamp the seals 14 against the cylinder 20 and to support the piston 16.

In this type of compressor—that is compressors used for compressing gas up to several thousand pounds per square inch—the seals are commonly held in sealing relation with the piston by means of the pressure of the fluid being pumped. As a consequence of this relatively high force exerted on the seal, considerable friction is generated between the seal and piston 16.

A common means for cooling the piston is to drill a central passage in the piston and supply oil to the passage to conduct the heat from the piston. The difficulty with this construction is that it is quite expensive and to some extent weakens the piston structure. The present invention avoids these difficulties with a cooling system whereby a cooling fluid, such as air, oil or an inert gas, is conducted around the periphery of the piston.

In furtherance to this end a cooling fluid distributing ring is positioned to direct cooling fluid on the piston at or near the outer end piston seal. More particularly a bearing element 24 mounted in the cap 22 and encircling the piston 16 is formed with inner and outer peripheral grooves 26 and 28, respectively, communicated through holes 30. Cooling fluid is supplied to the outer grooves 28 through a passage 32 formed in the cap 22.

With this cooling system cooling fluid is conducted from a supply (not shown) through the passage 32 around the groove 28 and thence through the holes 30 and directed at the periphery of the piston 16. The piston in reciprocating through the bearing is cooled along its length a distance equal to the piston stroke plus the width of the groove 26. Experience has shown that this method of cooling is extremely effective for the length

2

of the piston exposed directly to such fluid. Moreover it maintains this portion of the piston sufficiently cool such that the free end portion of the piston not exposed directly to such cooling fluid is also maintained at a satisfactory low temperature in that the heat from the latter portion of the piston is conducted along the piston to the directly cooled portion.

The cooling fluid after contact with the piston flows therealong to the exterior, or outer end, of the cap 22. When it is desired to save the cooling fluid for recirculation fluid, as for example when such fluid is oil, a drain chamber may be provided in the casing part 34 in which a drain port 36 is provided.

FIG. 3 illustrates another form of the invention shown in FIGS. 1 and 2 disclosing a structure which serves as another way of effectively cooling the piston, and of saving the cooling fluid for recirculation. All parts corresponding to those in FIGS. 1 and 2 have the same numerals with the addition of a prime (').

In the present form of the invention the cooling fluid is not allowed to flow to the outer end of the cap 22' and into the drain shown in FIG. 1, but is directed from one end of the groove 26' to the opposite end thereof to exhaust passageways which communicate with the groove 26' and the supply (not shown). Accordingly, an exhaust passage 38 extends through the lower half of the cap 22' and communicates with the outer end portion 39 of the inner peripheral groove 26' through exhaust passage 40 of the bearing element 24'. The passage 38 extends from the passage 40 to a supply (not shown) and conveys exhaust fluid thereto.

The exhaust passage 40 comprises an outer peripheral groove 42 and a port 44 communicating the outer end portion 39 of the inner peripheral groove 26' with the groove 42. The outer peripheral groove 28' and holes 30' are longitudinally displaced from the exhaust passage 40 with the holes 30' communicating with the inner end portion 41 of the groove 26'.

In order to limit leakage along the rod 16' seals 46 are provided on opposite ends of the bearing element 24'. The seals 46 encircle the rod 16' and are housed in undercuts 48 in opposite ends of said element 24'. The seals 46 are held against longitudinal movement by clamping means, or cover, 50 which is secured to the cap 22' at the outer end thereof by bolts 52. The clamping means 50 abuts one end of the outer seal 46 and element 24' and holds said element 24' against seal 14'.

In addition to the seals 46, O-rings 54 serve to limit leakage of coolant between complementary fitted parts.

With this cooling system cooling fluid is conducted from a supply (not shown) through passage 32' around the groove 28' and thence through holes 30' and directed at the periphery of the rod 16' located at the inner end portion 41 of the groove 26'. Therefore, the coolant first comes in contact with the piston portion nearest its free end and flows away therefrom to the outer end portion 39 of the groove 26' into the passage 40 and back to the supply (not shown) via exhaust passage 38. It is to be noted that the coolant flows from one end of the groove 26' to the opposite end thereof, thereby obtaining maximum effect from the coolant.

While I have shown and described two forms of my invention, it is to be understood that various changes and modifications may be made without departing from the spirit of the invention as set forth in the appended claim.

I claim:

A cooling ring for admitting coolant fluid to a piston reciprocating within a casing and having a rod for reciprocating the piston and said casing having an inlet for coolant fluid, said cooling ring comprising, a central bore through the ring for receiving said piston rod, an outer annular groove about the outer periphery of said ring

for receiving coolant fluid from said inlet, an inner annular groove about the inner periphery of said ring, said inner annular groove being longitudinally larger than said outer annular groove, a plurality of passageways communicating between one end of said outer annular groove and one end of said inner annular groove to conduct coolant fluid against said piston rod, an exhaust port in the other end of said inner annular groove, through which the fluid in said inner annular groove may be exhausted, a second outer peripheral groove communicating 10 with said exhaust port for exhausting said inner annular groove, and undercuts located in the opposite ends of

⁴
said ring for housing seals thereby limiting leakage along said rod.
